UNITED STATES PATENT OFFICE.

WILLIAM A. SHELLEY, OF PORTLAND, OREGON, ASSIGNOR TO JOSEPH L. HOFFMAN, OF PORTLAND, OREGON.

OIL-BURNER.

1,169,433.

Specification of Letters Patent. Patented Jan. 25, 1916.

Application filed June 18, 1914. Serial No. 845,948.

To all whom it may concern:

Be it known that I, WILLIAM A. SHELLEY, a citizen of the United States, and a resident of the city of Portland, county of 5 Multnomah, State of Oregon, have invented a certain new and useful Improvement in Oil-Burners, of which the following is a specification.

My invention relates to heating devices 10 using inflammable fluids, such as hydrocarbon oils atomized by supplementary fluid blasts so as to produce an intensely hot flame.

My invention has for its object the providing of a burner producing a flame projecting in the form of a sheet, and embodying means by which the projection of the sheet of flame may be controlled so that it may be projected at any convenient angle.

20 A common experience in oil burners is, that because of the discharge orifice of the fuel oil, or the atomizing fluid or blast becoming partly clogged, the sheet of flame emanating from the burner is deflected, and 25 its efficiency is in this wise deteriorated. And if a very hot flame is directed against the boiler tubes disastrous results may occur.

To overcome such undesirable condition 30 is one of the main objects of my improved burner.

I attain my object by the combination of a burner comprising a fuel oil discharge spout, and atomizing-fluid or blast spouts 35 located on either side of, and in a vertical plane with said oil spout, the floor of the fuel spout being made with a longitudinally projecting lip, and the overlying blast spout having a discharge orifice impinging 40 at an angle upon said projecting lip of the oil spout, thereby promoting a thorough atomizing of the liquid fuel and the intermixing of air therewith. The underlying blast spout has a discharge orifice discharging 45 parallel to said projecting lip of the fuel spout, and the supply pipes connected with said spouts have each a controlling valve located at a distance from the nozzle. By said arrangement the fuel orifice of the 50 nozzle normally tends to discharge the fuel in the form of a sheet straight ahead, and the underlying blast spout forms a supporting fluid stratum for the projected flame; and by relatively regulating the pressure of fluids discharged through the over-

lying and underlying blast spouts respectively, the direction of the flame can be controlled and adjusted without access to the nozzle of the burner being required. By such means there is overcome any temporary 60 clogging of the discharge orifices of either of said spouts, and the divergence of the flame, as mentioned, may be corrected.

The details of construction and operation of my invention are hereinafter fully described.

In the accompanying drawings: Figure 1 is a perspective view showing my burner as arranged in practice; and Fig. 2 is a vertical sectional detail of the nozzle of my 70 burner.

My burner comprises a body, which may be a one-piece casting, *a*, provided with partitions, *b*, dividing the interior into a fuel-oil spout, *c*, an overlying atomizing fluid or 75 blast spout, *d*, and an underlying atomizing fluid or blast spout *e*. The discharge orifice of the fuel spout, *c*, is contracted, as shown at *f*, and the floor of this spout is made with a longitudinally projecting lip *g*. The discharge orifice *h* of the overlying blast spout *d* is curved downward so as to cause the blast of atomizing fluid to impinge upon the lip *g* at an angle and intersect the jet of fuel oil, thus insuring a thorough inter- 85 mixture of air with the combustible stream of oil ejected from the discharge orifice *f*. The discharge orifice, *i*, of the underlying blast spout *e* discharges a blast underlying the jet of oil discharged from the orifice *f* of 90 the spout *c*. The inner end of the body, *a*, has threaded orifices in which are inserted the oil pipe *j*, and the steam or fluid pipes, *k*, *l*, provided with controlling valves *m*, *n*, *o*, so that the pressure of the fuel, and likewise the force of the blasts emitted through the pipes *k* and *l*, may be so adjusted as to 95 properly project the flame as mentioned.

It will be observed, by looking at the discharge orifice of the nozzle in Fig. 1, that 100 the discharge orifices are made in the form of a transversely elongated slot, in order to spread the flame in the form of a horizontal sheet.

I claim:

In a fuel-oil burner, a nozzle consisting of a body provided with internal, longitudinal, horizontal partitions dividing the body into three independent chambers arranged in vertical alinement, the discharge end of 110

said chambers being contracted into substantially equal size, slot-like, horizontally extending orifices, the discharge orifices of the upper two chambers merging into a single discharge orifice at the front of the burner, and the discharge orifice of the lowermost chamber being below and independent of said single or combined orifice, the central chamber constituting the fuel-oil spout, the chambers on either side of the

fuel-oil spout constituting the atomizing fluid-spouts, the upper atomizing spout being adapted to so discharge its jet, as to intersect the jet of fuel-oil, and means for varying the relative force of the jets delivered by the atomizing fluid-spouts.

WILLIAM A. SHELLEY.
